William M. Hawkins

INVENTOR -

James McCormick

UNITED STATES PATENT OFFICE.

JAMES MCCORMICK, OF POTSDAM, NEW YORK.

VEHICLE-SPRING.

SPECIFICATION forming part of Letters Patent No. 360,710, dated April 5, 1887.

Application filed December 6, 1886. Serial No. 220,849. (No model.)

To all whom it may concern:

Be it known that I, JAMES MCCORMICK, of the town of Potsdam, county of St. Lawrence, and State of New York, have invented certain new and useful Improvements in Vehicle-Springs, of which the following is a description, reference being had to the accompanying drawings, in which similar letters of reference represent like parts, and in which—

10 Figure 1 represents a perspective view; Fig. 2, a longitudinal section through one of the springs, and Fig. 3 a central transverse section.

15 My invention has relation to certain new and useful improvements in vehicle-springs of the class generally employed in side-spring buggies, light wagons, buckboards, &c., in which both wood and metal are combined to form a composite spring.

20 To this end it consists in a certain arrangement of parts, as will be hereinafter fully described and particularly pointed out.

25 At or near the extremities of the forward head-block or bolster A, I fasten, by means of ordinary bolts or clips, the front ends of two preferably arched or upwardly-bent strips, B, of wood of elastic character. Upon the under side of each of these strips of wood, throughout its entire length and in close contact therewith, is placed a leaf of steel, E. Each of these compound springs of wood and steel is also bolted or clipped to the rear axle, D. The springs so formed of wood and steel are thus securely and rigidly attached both at front and rear to an unyielding portion of the body-gear or 30 frame of the vehicle and make a firmly-supported but elastic cushion for the box or body. Upon the upper sides of the springs thus formed I now secure by a centrally-located through-bolt, e, or equivalent means, a series of 35 steel leaves, C, each of diminishing length.

40 To further strengthen the frame or body-gear, I secure at points near the center, upon each side thereof, a light metal or wooden cross-bar, F F, by means of clips f passing wholly over and encompassing both the metal 45 and wooden springs, and being fastened securely within the extremities of the cross-bars, respectively. Free longitudinal play is thus permitted to each of the individual members 50 of the entire series of leaves above the wooden springs, but checking any tendency therein to

lateral rack or strain and firmly holding them against overstrain upon the central through-bolts.

55 The head-block or bolster is mounted upon the forward axle in the usual manner. In the construction which I have herein described is provided, as will be at once apparent to those skilled in the art to which the improvement appertains, a spring-frame at once light, strong, 60 elastic, and firmly braced. Full play is provided for the elastic parts without the loose shackles heretofore employed, and in which the "rebound" is not only unpleasant to the occupant of the vehicle, but is nearly always a 65 source of accident and danger as well.

70 The wooden spring in the improvement described, being made somewhat broad, fulfills the various functions of a reach for the vehicle and a brace for the entire spring, preventing 75 in substance all side sway of the body, as well as controlling most effectively the rebound, with consequent liability of breakage, whenever the vehicle meets with a sudden jolt by reason of an obstruction in the road. At the same time the entire spring yields readily 80 downward with a slow and easy movement, the degree of which is determined by the weight put upon it by reason of the lessened friction of the several members of the spring in their play upon each other. It affords, moreover, a ready and comparatively inexpensive frame or gear upon which to set the body or box of the vehicle.

85 It is manifest that certain changes might be made in the construction described, by which the functions and advantages pointed out would all be retained. These changes, coming within the scope of my invention, I wish it distinctly understood I do not hereby release.

90 It has been heretofore proposed to place beneath a metal-leaf side-spring, for the sake of securing firm shackle-bearings at ends thereof and giving increased longitudinal strength 95 thereto, a double layer or layers of rubber or of composite rubber and cloth belting. To obviate some of the disadvantages which have been heretofore pointed out, a construction of springs has also been suggested in which a 100 pair of metal-leaf springs centrally secured one upon the other are seated upon the under

side of a thick bar of wood within a longitudinal groove therein; but in this instance the grooved bar is relied upon to act as a stay or brace only to receive and distribute the action

5 of the metal springs. In neither of the constructions thus proposed is a compound spring of thin highly-elastic wood and metal firmly secured together at each extremity employed as a superstructure upon which rests a series 10 of steel leaves centrally secured to the said superstructure, but free to play from that point to their extremities, whereby a very light, sensitively-elastic, and comparatively inexpensive spring is produced.

15 Therefore, what I claim as new, and desire to secure by Letters Patent of the United States, is—

1. A compound spring of wood and steel secured together at each extremity and provided upon its upper face with a series of steel 20 leaves, as set forth.

2. A compound spring of wood and steel securely attached at each extremity and provided upon its upper face with a series of steel 25 leaves centrally secured thereto, but with free extremities, as set forth.

3. A pair of longitudinal compound springs of wood and steel securely attached at front and rear to the rigid parts of a vehicle-gear,

as the front head-block and the rear axle, in 30 combination with a series of metallic leaves centrally fastened to the upper faces thereof, as set forth.

4. A pair of longitudinal compound springs of wood and steel securely attached at front 35 and rear to rigid transverse parts of a vehicle-gear, as the front head-block and the rear axle, in combination with a series of metallic leaves centrally fastened to the upper faces thereof, and with a cross-brace upon each side of the 40 center of the said springs, as set forth.

5. A pair of longitudinal compound springs of wood and steel firmly affixed at front and rear to rigid transverse parts of a vehicle-gear, as the front head-block and the rear axle, in 45 combination with a series of metallic leaves centrally fastened to the upper faces thereof, and with a cross-brace upon each side of the center of said springs, provided at each end with a clip which wholly encompasses but 50 does not hinder the longitudinal play of the series of metallic leaves, as set forth.

In testimony whereof I have hereunto set my hand in the presence of witnesses.

JAMES McCORMICK.
